PRINTING ATTACHMENT FOR ADDING MACHINES

Andrew Oakland, Stambaugh, Mich.

Application January 19, 1931. Serial No. 509,864

3 Claims. (Cl. 101—228)

This invention relates to an improved attachment for adding machines and more particularly to a printing attachment for adding machines.

One of the objects of the present invention is the provision of an improved type of printing attachment adapted to be used in connection with various types of adding machines whereby the usual paper strip used in connection with adding machines has applied to one face thereof, a series of printed indications which can be arranged in consecutive order throughout the length of the strip and is printed thereon prior to the use of the strip for indicating thereon the various amounts to be totaled.

Another object of the present invention is the provision of an adding machine attachment whereby the usual paper strip which is used for indicating thereon the numbers to be added, as well as the total, etc., can have printed on the reverse side thereof various indications which can be used for adding purposes, whereby a merchant can advertise to the public his merchandise and disclose to the public an advanced notation of any sales or the like which are to be carried out.

A further object of the present invention is the provision of an attachment for adding machines whereby the usual strip of paper used in connection with adding machines has printed or indicated thereon, suitable notations for the benefit of the merchant, or other party using the adding machine, and the same is applied to the side of the strip, which at the present time is blank, and unused after being passed through the machine, so as to utilize both sides of the paper and advertise the merchandise of the merchant.

With the above and other objects in view, the invention consists in the novel features of construction, the combination and arrangement of parts hereinafter more fully set forth, pointed out in the claims and shown in the accompanying drawings wherein:

Figure 1 is a side elevation of an adding machine, illustrating the application of my printing attachment, with parts thereof broken away and illustrated in cross section;

Figure 2 is an elevation of one side of the paper, showing the advertising or other notations indicated thereon;

Figure 3 is a side elevation with the outside cover in position;

Figure 4 is a vertical section on the line 4—4 of Figure 3;

Figure 5 is a detailed section on the line 5—5 of Figure 4;

Figure 6 is a detailed side elevation of the printing roll, showing another application of the type; and,

Figure 7 is a detailed side elevation illustrating the application of the chains and sprockets in connection with the improved device.

Referring more particularly to the drawings, 1 indicates the body of a well known type of adding machine, provided with the usual operating handle 2 which is attached to a rockable shaft 3. Mounted upon this shaft is an arm 4 connected with a link 5 which in turn is connected to the bell crank 6.

The bell crank 6 actuates the lever 7 attached to shaft 8 and mounted on this shaft is a rockable member 9 which is adapted to actuate the usual pawl 10 which engages the ratchet 11 for rotating the feed roll 12 for the usual paper slip 75 upon which the indications of the machine are printed. The above is well known construction and forms no part of my invention.

Arranged at the rear of the machine 1 is a frame 13 which supports the operating mechanism for my improvement. This frame is connected by means of a bottom cross piece 14 and a transverse bolt 15. A removable cover portion 16 is provided and a removable side portion 17 closes the back of the frame and embraces the 85 side portions thereof, as shown in Figure 1.

The shaft 18 is carried by the frame 13 and supports a paper roll 19. The paper on this roll is fed upwardly over the guide roll 20 and then extends forwardly over the support 21 where it 90 passes down around the roll 12.

Within the frame 13, an inking roll 22 is supported which is preferably positioned to be contacted by the type 23 in the type roll 24.

The rolls 20 and 22 are positioned in close proximity to the type roll 24, so that as the paper is fed from the roll 19 over roll 20, the type 23 will engage the inking roll 22, and the paper, as it passes over the roll 20 for printing thereon various indications such as illustrated in Figure 100 2. The lines of indications which in the present instance are indicated at 25, are arranged in equal spaced relation due to the relative position of the type with respect to the roll 24, and the even rotation of this roll with the discharge of 105 the paper from the roll 12.

The pawl has pivotally connected thereto a link 26 which is provided at its outer end with a U-shaped portion 27 having a transverse pin 28 carried thereby and adapted to engage the 110

teeth of the ratchet 29. This ratchet 29 is mounted upon the shaft 30 which supports the type roll 24. The type roll 24 is yieldably retained in engagement with the inking roll 22 and the guide roll 20, by means of spring members 31 which are arranged upon opposite sides of the frame 13 as shown in Figure 4, and engage the shaft 30. The ends of each spring are attached to the outside walls of the frame 13 at 10 a point below the uppermost position of the shaft 30, as shown in Figure 1, whereby the shaft 30, which is mounted within suitable slots in the side walls of the frame 13 will be urged downwardly.

15 The link 26 is yieldably retained in position with respect to the ratchet wheel 29 by means of a coil spring 32 as shown in Figure 1 to positively assure engagement of the pin 28 with the teeth of the ratchet 29 when link 26 is moved 20 forwardly through actuation of the main parts of the machine.

In the construction of the type roll 24, it will be noted that spacing members 33 are secured to the roll 24, so that the removable type members 34 can be positioned between the spacing members and yieldably retained in position.

Another form of type roll is illustrated in Figure 6, wherein the main type roll 24' has a removable belt or endless portion 35 mounted thereon, and the type members 36 are formed integral with the same.

This permits a number of indications to be quickly applied to the exterior of the roll 24', or removed therefrom. In Figure 7, I have illustrated another form of the invention wherein the ratchet 29 is replaced by means of a sprocket 37 and a sprocket 38 can be mounted upon the supporting shaft of the roll 12 and these two sprockets can be connected by means of a chain 39, illustrating that various ways can be provided for connecting up the type roll with the feed roll 12, so as to provide simultaneous action between these two rolls.

As shown in Figures 3 and 4, the frame 13 is normally enclosed by means of a housing 40 which can be set down over the frame, and this housing is provided with a removable cover portion 41. A finger wheel 42 is attached to the outer end of the shaft 30 for manipulating the type roll 34. It is believed from the foregoing that I have provided a comparatively simple and inexpensive attachment for adding machines, wherein the usual blank side of the paper which is used for indicating the figures thereon, can have printed on the reverse side, which at the present time is blank, a series of advertising or any other similar type of notations which the merchant desires to use.

From this it will be apparent that if a merchant contemplates a sale within a day or two, or if he is placing on sale merchandise at a particularly low price, this can be indicated on the usual blank side of the paper and disclose the facts to the purchasing public.

60 The type on the roll can be so arranged that either short or long strips can be torn from the machine, but the advertising or indications

thereon will be so arranged as to intelligently indicate to the purchaser what is being placed on sale, etc.

This device is in the form of an attachment and can be readily connected up to well known makes of adding machines on the market at the present time, with comparatively no change at all in the machine, and will prove a great benefit to a merchant.

In order to maintain the attachment in close proximity to the machine 1, the brackets 43 are provided with lateral ears 44 and rivets 45 are used for connecting the frame 13 with these ears. The lower portion of the frame carries a lateral projecting arm 46 which extends beneath the adding machine and is attached thereto by the screw member 47.

While I have shown and described the preferred embodiment of my invention, it will be apparent from the foregoing that slight changes may be made in the construction when putting the invention into practice without departing from the spirit of the same or the scope of the appended claims.

I claim:

1. An attachment for adding machines including a frame, means for supporting the frame at one end of the adding machine, a support for a paper supply roll carried by the frame, a guide roll above the supply roll, an inking roll adjacent the guide roll, a printing roll positioned above and in intimate contact with the inking roll, and the guide roll, whereby to press upon the paper as it passes over the guide roll predetermined impressions, means for guiding the paper from the guide roll around the feed roll of an adding machine and manually controlled means for simultaneously imparting movement to the type roll and the feed roll of the adding machine.

2. In combination with an adding machine including a feed roll and manually controlled means for actuating the feed roll, of an attachment including a support for a paper supply roll, means for guiding the paper from the supply roll to the feed roll, printing mechanism, and means forming operative connection between the control means for the feed roll and the printing mechanism whereby to simultaneously actuate the printing mechanism upon the advancement of the feed roll.

3. In combination with a machine having a feed roll for a paper strip and manual means for actuating the roll, of an attachment for the machine for printing on one side of the paper strip including a supporting casing, means for securing the casing to the machine in rear of the feed roll, a support for rotatably carrying a paper supply roll in the casing adjacent to the lower end thereof, guide means arranged in the casing and disposed between the feed roll and the paper roll for receiving the strip, a rotatable printing roll mounted in the casing above the guide means for engaging the strip, and means operatively connecting the rotatable printing roll with the feed roll, whereby the same will be actuated synchronously with the feed roll.

ANDREW OAKLAND.
